UNITED STATES PATENT OFFICE.

JOHN CORNELIUS WILSON, OF BOSTON, MASSACHUSETTS.

ELECTRIC TIME-DETECTOR.

SPECIFICATION forming part of Letters Patent No. 351,681, dated October 26, 1886.

Application filed May 12, 1884. Serial No. 131,113. (No model.)

To all whom it may concern:

Be it known that I, JOHN CORNELIUS WILSON, of Boston, county of Suffolk, State of Massachusetts, have invented an Improvement in 5 Automatic Signal Apparatus for Watchman's Detection, of which the following description, in connection with the accompanying drawings, is a specification, like letters on the drawings representing like parts.

10 My invention relates to a signaling apparatus for detecting or indicating the movement of a watchman making his rounds, or for similar purposes, and has for its object to produce a definite signal whenever the watchman or 15 other person has failed to be present at the station within the proper period of time, the signal being characteristic of the station or locality at which it is placed, and thus indicating the exact station or point at which the 20 watchman has failed to appear.

The invention consists, mainly, in a clock-work or motor running at a definite rate of speed, adapted, when wound wholly up, to bring a transmitting mechanism into operation 25 at the end of a definite interval of time after it has been thus wound, but preventing the said transmitting device from coming into operation if the motor is rewound within the said interval of time, so that as long as the 30 watchman returns to the station and rewinds the clock within the said interval of time no signal will be given; but if the watchman fails to rewind the clock within the said interval of time the said clock will cause a signal to be 35 transmitted, the said signal being preferably a number-signal indicating the station from which it is received, like the well-known fire-alarm or district-signal boxes.

Figure 1 represents in front elevation a sufficient portion of a signaling device to illustrate 40 this invention. Fig. 2 is a sectional detail thereof, and Fig. 3 a diagram showing the specific connections of the different parts.

The signaling apparatus consists, essentially, 45 of a clock or train of wheel-work, *a*, terminating in a suitable escapement, *b*, by which it is caused to move at a substantially uniform rate, the said clock-work or motor being of any usual construction. One of the arbors of the 50 said wheel-work, as *c*, which rotates at a suitable speed, is provided with a signal-transmitting device or break-wheel, *d*, the surface

of which co-operates with a spring, *e*, and has insulated spaces, which interrupt a current flowing from the said break-wheel to the said 55 spring, thus producing a number-signal indicating the number or location of the instrument, as is common in signaling apparatus. The said wheel *d* is connected with the main circuit or line *L*, (see Fig. 3,) entering the apparatus, and the spring *e* is connected with the continuation *L'* of the said circuit, leaving the apparatus at the other side, as shown in Fig. 3. In order to prevent the said break-wheel from transmitting its signal at every rotation, it is normally shunted, or the portions 60 *L L'* of the line electrically connected by another wheel or disk, *f*, and spring *g*, moving at a slower rate of speed than the wheel *e*, the said wheel *f*, however, having an insulated space, 65 *f'*, of sufficient length to occupy a period of time in passing under the spring *g* equal to that occupied by one or more complete rotations of the wheel *d*, so that during the time that the insulated portion *f'* is passing beneath the spring 70 *g* the wheel *d* and spring *e* will be in circuit, unless otherwise shunted or removed therefrom. The said wheel *d*, as well as the one *f*, is also normally shunted by the controlling device, 75 consisting of a disk, *h*, connected with the winding-arbor *i* of the clock, and moving therewith when it is turned by the usual key, a portion of which is shown at *K*, Fig. 2, and also rotating with the said arbor as the clock runs down. A stop, *k*, fixed on the framework, co-operating with a stop projection, *k'*, on the disk, limits the movement of the said disk in winding up the clock, and the power of the actuating spring or weight acting on the arbor *i* is transmitted therefrom to the wheel- 80 work by a ratchet, *i'*, fixed on the said arbor, and one or more pawls, *i''*, pivoted on one of the gears of clock-work, which is loose on the 85 said arbor, all as usual.

The periphery of the controlling-disk *h* is 90 provided with one or more insulated portions, *m*, and the co-operating spring *n* rests upon the periphery of the said disk in such a position that when the clock is wholly wound up it will touch the periphery at a considerable 95 distance from the said insulated space that will first reach it, so that as the disk *h* rotates with the train of wheel-work in running down, a definite predetermined interval of time, which

may be of any suitable length—as, for instance, an hour (more or less)—will elapse after the clock is wound up before one of the insulating-spaces *m* will reach the spring *n*, thus opening the line *L L'* between them. The said insulated spaces *m* are of sufficient extent to retain the shunt or branch circuit thus opened at *m n* during at least one complete rotation of the wheel *f*, so that the latter will have an opportunity to open the shunt or branch circuit at *f' g*, leaving the main circuit under control of the disk *e* and the spring *d* during one or more complete rotations of the said disk, which will thus produce a series of interruptions in the 15 current or transmit its signal in the well-known manner.

The apparatus is shown in Figs. 1 and 3 in the position to transmit a signal, the time that has elapsed since the last winding of the motor being greater than it is intended to have elapse before the watchman again comes to wind the motor. If, however, the motor had been rewound before the insulated portion *m* arrived at the spring *n*, the disk *h* would have 20 been turned back and the spring *n* would have remained in metallic connection therewith, keeping the wheel *e* shunted, so that no signal could be transmitted until the end of another 25 interval of time beginning from the time when the motor was thus wound.

In case the motor should not be rewound at all, the disk *h* will continue to rotate in the direction of the arrow thereon for a complete 30 rotation or more, if desired, and the portions *m*, being arranged at equal distances around its periphery, would throw the signal into operation at the end of each period of time occupied by the disk *h* in traveling a distance equal to that between the said insulated 35 portions *m*.

In case it is desired to have the disk *h* make more than one revolution, a suitable stop will 40 have to be substituted for the one *k k'*, such stops being well known in connection with clock-work.

If desired, the entire apparatus may be removed from the circuit or shunted, during the winding of the motor, by the device best shown in Fig. 2, in which the key *k* is free to move 45 longitudinally for a short distance on the arbor *i*, and is normally held by a spring, *o*, disengaged from the squared portion of the said arbor *i*, so that the latter cannot be turned by the key before the said key is pressed forward 50 in the direction of the arrow, to engage the said squared portion. In this forward movement the key engages a spring, *p*, connected with the portion *L* of the line, causing the 55 said spring to engage the disk *h*, that, as before mentioned, is connected with the portion *L* of the line, thus shunting the wheels *f* and *e*.

It is obvious that, if desired, the wheel *f* may be omitted, and the portion *m* of the disk *h* made of sufficient width to bring the wheel 60 *d* into circuit during one or more complete rotations; but it is preferable to employ disk *f*,

as the latter, being positively connected by gearing with the disk *e*, retains a definite relation thereto, so that the disk *d* may be brought into circuit always at the same point in its rotation, and retained there during one or more complete rotations. 70

Any desired number of the signaling-instruments will be placed in a single circuit connected with a central or main station, so that 75 an attendant at the said station will know whether or not the watchman is attending to his duty, and, if not, he will know just where the neglect has occurred.

I claim—

1. The combination, substantially as herein-before set forth, of a clock or motor, a signal-transmitting device constructed and arranged to send a determinate signal characteristic of its locality, actuated by said motor, and a controlling device moved forward by said motor, and backward or restored to its normal condition by an operator, said controlling device being constructed and arranged to cause the signal-transmitting device to operate after being moved forward by the motor a predetermined interval of time unless previously moved backward or restored to its normal condition by an operator. 85

2. The clock or motor comprising a train of 95 wheel-work, one of the arbors of which is provided with a break-wheel for producing a series of interruptions in an electric current, combined with another wheel carried by another arbor controlling the same circuit and 100 limiting the period of operation of the break-wheel, and a controlling device operatively connected with the winding-arbor of the clock and controlling the break-wheel circuit, said 105 controlling device being constructed and arranged to retain the break-wheel inoperative for a definite period of time while moved forward by the actuating member of the motor, but to change the circuit and render the break-wheel operative after the predetermined period has elapsed, unless the winding-arbor is 110 rotated to wind the motor, and thereby move the controlling device backward or restoring it to its normal position, substantially as described. 115

3. The combination, substantially as herein-before set forth, of a clock or motor, a signal-transmitting device constructed and arranged to send a signal characteristic of its locality, a shunt-circuit for the said signal-transmitting device, and a circuit-controller for the said shunt-circuit, normally retaining the signal-transmitting device inoperative, but constructed and arranged to be moved forward by the actuating member of the motor and to change 120 the condition of the circuit after a definite period of time has elapsed, and also capable of being moved backward or restored to its normal condition at any time prior to changing the condition of the circuit, to thereby continually 125 render the signal-transmitting device inoperative. 130

4. A signal-transmitting device and controlling device therefor operated by the actuating member of a clock or motor, combined with a circuit-controlling device operated by the key of the said motor, whereby the transmitting device is rendered inoperative while the motor is being wound, substantially as described.

In testimony whereof I have signed my name to this specification in the presence of two subscribing witnesses.

JOHN CORNELIUS WILSON.
